ICE-CRACKING IMPLEMENT

Thomas B. Aldrich, West Nyack, N.Y., assignor to
Frank W. Earnest, Jr., Wilkes-Barre, Pa.

Filed July 3, 1963, Ser. No. 75,648

Term of patent 14 years

(Cl. D44—29)

FIGURE 1 is a perspective view of an ice-cracking implement, showing my new design;

FIGURE 2 is a top plan view thereof on an enlarged scale;

FIGURE 3 is a side elevational view thereof; and

FIGURE 4 is an end elevational view thereof.

I claim:

The ornamental design for an ice-cracking implement, as shown.
